UNITED STATES PATENT OFFICE.

DANIEL BRANDENSTEIN, OF NEW YORK, N. Y., AND JACOB FISCHER, OF ROSEVILLE, NEW JERSEY.

PEDAL-OPERATED MECHANISM.

1,327,137.

Specification of Letters Patent.

Patented Jan. 6, 1920.

Application filed May 6, 1919. Serial No. 295,124.

To all whom it may concern:

Be it known that we, DANIEL BRANDENSTEIN, a citizen of the United States, and a resident of the borough of Manhattan, city, 5 county, and State of New York, and JACOB FISCHER, a citizen of the United States, and a resident of Roseville, Essex county, State of New Jersey, have jointly invented certain new and useful Improvements in Pedal-Operated Mechanism, of which the following is a description.

This invention relates to pedal-operated mechanism for sewing machines and the like, and has for its object to enable the pedal to be readily folded up, out of the way, so that the floor may be swept thoroughly under the sewing machine or other mechanism beneath which the pedal is located.

To this end, the invention consists in certain features of construction and relative arrangement, as will be described hereinafter and particularly pointed out in the appended claims.

Without intending to limit ourselves to the specific example shown (which may be modified in various ways while remaining within the scope of the appended claims), we will now explain in detail the preferred embodiment illustrated by the accompanying drawings, in which Figure 1 is a perspective view of the novel pedal arrangement; Fig. 2 is a side elevation of the lower part of the device, with the pedal swung up to the inoperative position; Fig. 3 is a partial horizontal section substantially on line 3-3 of Fig. 2, but with the pedal swung down to its operative position; and Fig. 4 is a partial vertical section on line 4-4 of Fig. 3.

The mechanism is illustrated in connection with a clutch of a character well-known in the operation of sewing machines. A designates a post with a suitable bracket B to which is pivoted at D a lever E having an arm E' controlling the position of a clutch member located in the casing F and permanently driven in any well-known or approved manner. Another arm E'' of said lever carries the usual brake shoe (not shown) adapted to engage the customary pulley (not shown). J is the customary belt extending from the pulley upwardly to the sewing machine. In the well-known manner, swinging the lever E down at the left-

hand end (Fig. 1) will move the brake shoe 55 to the inactive position and cause the belt J to be driven, while the opposite movement (under the influence of a spring K) will stop the drive of the belt and apply the brake.

The lever E is connected pivotally at L 60 with a downwardly-extending actuating rod, preferably extensible for ready adjustment as by making said rod of two sections M, M', passing through parallel sockets of a connecting member N, to which they are secured by set screws O. The lower end of the actuating rod is connected pivotally with the pedal P, the pivot Q extending from front to rear. At each side the pedal is provided with lugs or trunnions P', P'', 70 in transverse alignment with each other. The trunnion P', on the side opposite the actuating rod, simply rests in a stationary open-top socket or bearing R secured to the floor. The other lug P'' extends into a slot 75 S' of a preferably cylindrical member S journaled in the stationary bearing R' said member S turning about a transverse horizontal axis in alignment with the axis of the bearing R. The member S may be held 80 against axial displacement as shown in Fig. 3, by means of an interior shoulder and by means of nuts T screwed on a threaded axial extension S''. The connection of the pedal lug P'' with the journaled or swivel member S is effected by means of a pivot pin U which is permanently in exact or approximate alignment with the pivot Q, so that the pedal P may be swung readily on the axis of the pivots Q, U, from the normal or operative lower position shown in Fig. 1 to the inoperative raised position Fig. 2, the open top of the bearing R permitting the pedal to thus swing up to the inactive position, or back to the lower position. Preferably a 85 locking device is provided to hold the pedal in the upper position, for which purpose we may employ a latch V pivoted at W to a bracket X secured rigidly to the actuating rod, the pivot W being parallel to the axis 90 Q, U, or approximately so. This latch is adapted to hook over the side edge of the pedal P opposite to the edge at which the pivot Q is located, a spring Y serving to hold the latch in locking position. The latch 95 and its carrying bracket may be adjustable vertically along the actuating rod, as by passing the rod section M through a vertical

100
105

opening or socket on the bracket X, a set screw Z holding the bracket in place after such adjustment.

The pedal, when swung from its active 5 to its inactive position, will push the latch V upward, and the latter will then snap back over the edge of the pedal.

It will be obvious that the new construction does not interfere in the least with 10 the usual operation of the pedal in which it swings about the transverse axis of the bearings R, R'. In addition to this customary movement, the pedal can be swung about the axis Q, U (see dotted line in Fig. 15 1), and when in the upper position (Fig. 2) the pedal leaves a clear space on the floor between the two bearings R, R', so that the floor may be swept readily at this 20 place; which is but poorly accessible with the usual pedal constructions.

The construction shown at P'', Q, R', S, constitutes a universal connection between 25 the pedal and the bearing R', and while we prefer the construction shown, other forms of universal joints might be employed.

We claim:

1. In pedal-operated mechanism, spaced 30 stationary bearings one of which has an open-top socket, and a pedal located between said bearings and having at one side a lug or trunnion adapted for engagement with said open-top bearing, and at the other side a universal joint connection with the other bearing, whereby said pedal may be rocked 35 in said bearings, and also swung up on one bearing and out of the other bearing.

2. In pedal-controlled mechanism, spaced 40 stationary bearings one of which has an open-top socket, a pedal located between said bearings and having at one side a trunnion adapted for engagement with said open-top bearing and at the other side a lug projecting in the opposite direction, a swivel member journaled in the second bearing about 45 the transverse axis of both bearings, a pivot pin perpendicular to said axis and connecting said lug with said swivel member, and an actuating rod connected with said pedal at a distance from said lug by a pivot joint the 50 axis of which is in alinement with the axis of said pin.

3. In pedal-controlled mechanism, spaced 55 stationary bearings, and a pedal located between said bearings and connected with one of them by a universal joint, while arranged to be lifted out of engagement with the other bearing.

4. In pedal-controlled mechanism, spaced 60 stationary bearings, a swivel member connected with one of said bearings to turn about the transverse axis of both bearings, a pedal adapted for loose engagement with

the other bearing so that it may be lifted therefrom, and a pivot pin perpendicular to the axis of said swivel member and connecting said pedal with said member. 65

5. In pedal-controlled mechanism, spaced stationary bearings, a swivel member connected with one of said bearings to turn about the transverse axis of both bearings, 70 a pedal adapted for loose engagement with the other bearing so that it may be lifted therefrom, a pivot pin perpendicular to the axis of the swivel member and connecting said pedal with said member, and an actuating rod connected with said pedal at a distance from the swivel member by a pivot joint the axis of which is in alinement with the axis of said pin. 75

6. In pedal-controlled mechanism, spaced 80 bearings, a pedal having a universal joint connection with one of said bearings and adapted for loose engagement with the other bearing, and an actuating rod connected with said pedal by a pivot joint the axis of which 85 passes through the center of said universal joint.

7. In pedal-controlled mechanism, spaced 90 bearings, a pedal having a universal joint connection with one of said bearings and adapted for loose engagement with the other bearing, an actuating rod connected with said pedal loosely on the side adjacent to the universal joint bearing, and a latch carried by said rod and adapted to 95 engage the pedal when swung away from the other bearing.

8. In pedal-controlled mechanism, a pedal 100 universally supported at one side so that it may be rocked and also swung out of the way upwardly.

9. In pedal-controlled mechanism, a pedal 105 universally supported at one side so that it may be rocked and also swung out of the way upwardly, a support adapted to be engaged by the other side of the pedal when the latter is lowered, and a latch for locking the pedal in its raised position.

10. In pedal-controlled mechanism, a 110 pedal universally supported at one side so that it may be rocked and also swung out of the way upwardly, and a latch for locking the pedal in its raised position.

11. In pedal-controlled mechanism, a 115 pedal universally supported at one side so that it may be rocked and also swung out of the way upwardly, and a support adapted to be engaged by the other side of the pedal when the latter is lowered.

In witness whereof we have hereunto set 120 our hands this 7th day of April, 1919.

DANIEL BRANDENSTEIN.
JACOB FISCHER.
